(57) **CLAIM**

The ornamental design for a seat, as shown and described.

DESCRIPTION

FIG. 1 is a left front perspective view of a seat showing my new design;

FIG. 2 is a front elevational view thereof;

FIG. 3 is a right side elevational view thereof;

FIG. 4 is a rear elevational view thereof;

FIG. 5 is a top view thereof;

FIG. 6 is a right rear perspective view thereof;

FIG. 7 is a left front perspective view of an alternate embodiment of my new design;

FIG. 8 is a right side elevational view thereof; and,

FIG. 9 is a top view thereof.

The bottom view is not shown and forms no part of the claimed design.
